UNITED STATES PATENT OFFICE.

GEORGE C. QUICK, OF CENTRALIA, ILLINOIS, ASSIGNOR OF ONE-HALF TO
THOMAS QUICK, OF ST. LOUIS, MISSOURI.

CHURN-MOTOR.

SPECIFICATION forming part of Letters Patent No. 253,424, dated February 7, 1882.

Application filed December 12, 1881. (No model.)

To all whom it may concern:

Be it known that I, GEORGE C. QUICK, of Centralia, in the county of Marion and State of Illinois, have invented a certain new and 5 useful Improvement in Churn-Motors, of which the following is a full, clear, and exact description, reference being had to the accompanying drawings, forming part of this specification.

My invention relates to that class of churn-motors which operate the churn by means of a gravitating weight; and my invention consists in the construction of the frame or derrick which supports the operating-weight, and also in the general construction of the operating mechanism.

In the drawings, Figure 1 is a side elevation. Fig. 2 is a top view of the operating mechanism, and showing the supporting-frame in section on line 2 2, Fig. 1; and Fig. 3 is a rear view with the churn removed.

A is the churn, which rests upon a projecting end, b, of the bottom of the box B, whose sides give journal-bearing to the shafts of the operating mechanism.

C is a standard or post stepped into the bottom of the box B. This post is made in two pieces, hinged together at c, so that the upper portion may be turned down, as shown by dotted lines, Fig. 1, for convenience in shipping the device. The upper portion is held in its working position by a key, c', passing through staples in the two members. On the top of the post C is a right-angle piece, C', which supports a pulley, C², over which the operating-rope D passes.

C³ is a brace.

E is the operating-weight secured to one end of the rope D, the other end of the rope D being secured to the drum F, whose shaft f has 40 journal-bearing in the sides of the box B. On one end of the shaft f, outside the box, is a crank, f', for turning the drum to wind the rope thereon. On the other end of the shaft f, within the box, is a loose cog-wheel, f², which engages with a pinion, f³, on one end of a shaft, f⁴, which also has journal-bearing in the sides of the box B. On the other end of the shaft f⁴ is a cog-wheel, f⁵, which engages with a pinion, f⁶, on one end of a shaft, f⁷, which likewise 45 has journal-bearing in the sides of the box. On the other end of the shaft f⁷, outside the box, is a crank-arm, f⁸.

f⁹ is a short arm or link connecting the crank

f⁸ with the vertical connecting-rod f¹⁰, whose upper end is adjustably connected to one end 55 of a horizontal arm, f¹¹, whose other end is adjustably connected to the dasher a' of the churn A. The arm f⁹ is adjustably connected to the crank f⁸, as shown in Fig. 8. The connections are made adjustable for the purpose of increasing or diminishing the stroke of the churn-dasher. The arm f¹¹ is fulcrumed at or near its center to a post, f¹², supported by a frame, f¹³. The rod f¹⁰ works in elongated holes in the outer ends of guide-arms f¹⁴, which are secured by their other ends to the frame f¹³.

The operation is as follows: The dasher of the churn being connected to the driving mechanism at the proper adjustment, according to the amount of cream in the churn, the rope D 70 is next wound upon the drum F by turning the crank f' until the weight reaches the top of the supporting-post. Rigidly secured to the end of the drum, or to its shaft, is a ratchet-wheel, h, which is engaged by a pawl, h', on the cog-wheel f². When the drum is turned to wind up the rope the pawl slips over the teeth of the ratchet-wheel, allowing the wheel f² to remain still, and when the rope is unwound from the drum the pawl engages with the ratchet-wheel, 75 80 which turns the wheel f², and through the system of gearing operates the churn-dasher.

When the rope is all wound upon the drum the crank is released and the weight gravitates and operates the parts.

The motive power may be increased or diminished by a change of different-sized weights. A small amount of cream would, as a matter of course, require less motive power than a large amount of cream.

Having thus described my invention, the following is what I claim as new therein and desire to secure by Letters Patent:

The combination of churn A a', connecting-arm f¹¹, fulcrumed on post f¹², frame f¹³, connecting-rod f¹⁰, guide-arms f¹⁴, arm f⁹, crank f⁸, box B b, gearing f⁷ f⁶ f⁵ f⁴ f³ f² f, drum F, crank f', ratchet-wheel h, pawl h', rope D, weight E, pulley C², and supporting-post C' C, all made substantially as and for the purpose 90 95 100 set forth.

GEORGE C. QUICK.
